[57] **CLAIM**

The ornamental design for a lock for luggage or similar type carrying container, as shown and described.

DESCRIPTION

FIG. 1 is an exploded perspective view of a lock for luggage or similar type carrying container showing my new design, the opposite side of the lock being the mirror image thereof;

FIG. 2 is a perspective view thereof showing the latching portion engaged with the received portion, the opposite side of the lock being a mirror image;

FIG. 3 is an exploded front view thereof, the rear view being substantially a mirror image;

FIG. 4 is an exploded left side view thereof;

FIG. 5 is a rear view of the latching portion of the lock;

FIG. 6 is a top plan view of the assembled lock view shown in FIG. 2;

FIG. 7 is a bottom plan view of the assembled lock view shown in FIG. 2;

FIG. 8 is an exploded perspective view of a second embodiment of my new design, the opposite side of the lock being a mirror image;

FIG. 9 is a perspective view thereof showing the latching portion engaged with the received portion, the opposite side of the lock being a mirror image;

FIG. 10 is an exploded front view thereof, the rear view being substantially a mirror image;

FIG. 11 is an exploded left side view thereof;

FIG. 12 is a rear view of the latching portion of the lock;

FIG. 13 is a top plan view of the assembled lock view shown in FIG. 9;

FIG. 14 is a bottom plan view of the assembled lock view shown in FIG. 9;

FIG. 15 is an exploded perspective view of a third embodiment of my new design, the opposite side of the lock being a mirror image;

FIG. 16 is a perspective view thereof showing the latching portion engaged with the received portion, the opposite side of the lock being a mirror image;

FIG. 17 is an exploded front view thereof, the rear view being substantially a mirror image;

FIG. 18 is an exploded left side view thereof;

FIG. 19 is a rear view of the latching portion of the lock;

FIG. 20 is a top plan view of the assembled lock view shown in FIG. 16;

FIG. 21 is a bottom plan view of the assembled lock view shown in FIG. 16;

FIG. 22 is an exploded perspective view of a fourth embodiment of my new design, the opposite side of the lock being a mirror image;

FIG. 23 is a perspective view thereof showing the latching portion engaged with the received portion, the opposite side of the lock being a mirror image;

(Description continued on next page.)

DESCRIPTION

FIG. 24 is an exploded front view thereof, the rear view being substantially a mirror image;
FIG. 25 is an exploded left side view thereof;
FIG. 26 is a rear view of the latching portion of the lock;
FIG. 27 is a top plan view of the assembled lock view shown in FIG. 23;
FIG. 28 is a bottom plan view of the assembled lock view shown in FIG. 23;
FIG. 29 is an exploded perspective view of a fifth embodiment of my new design, the opposite side of the lock being a mirror image;
FIG. 30 is a perspective view thereof showing the latching portion engaged with the received portion, the opposite side of the lock being a mirror image;
FIG. 31 is an exploded front view thereof, the rear view being substantially a mirror image;
FIG. 32 is an exploded left side view thereof;
FIG. 33 is a rear view of the latching portion of the lock;
FIG. 34 is a top plan view of the assembled lock view shown in FIG. 30;
FIG. 35 is a bottom plan view of the assembled lock view shown in FIG. 30;
FIG. 36 is an exploded perspective view of a sixth embodiment of my new design, the opposite side of the lock being a mirror image;
FIG. 37 is a perspective view thereof showing the latching portion engaged with the received portion, the opposite side of the lock being a mirror image;
FIG. 38 is an exploded front view thereof, the rear view being substantially a mirror image;
FIG. 39 is an exploded left side view thereof;
FIG. 40 is a rear view of the latching portion of the lock;
FIG. 41 is a top plan view of the assembled lock view shown in FIG. 37;
FIG. 42 is a bottom plan view of the assembled lock view shown in FIG. 37;
FIG. 43 is an exploded perspective view of a seventh embodiment of my new design, the opposite side of the lock being a mirror image;
FIG. 44 is a perspective view thereof showing the latching portion engaged with the received portion, the opposite side of the lock being a mirror image;
FIG. 45 is an exploded front view thereof, the rear view being substantially a mirror image;
FIG. 46 is an exploded left side view thereof;
FIG. 47 is a rear view of the latching portion of the lock;
FIG. 48 is a top plan view of the assembled lock view shown in FIG. 44;
FIG. 49 is a bottom plan view of the assembled lock view shown in FIG. 44;
FIG. 50 is an exploded perspective view of an eighth embodiment of my new design, the opposite side of the lock being a mirror image;
FIG. 51 is a perspective view thereof showing the latching portion engaged with the received portion, the opposite side of the lock being a mirror image;
FIG. 52 is an exploded front view thereof, the rear view being substantially a mirror image;
FIG. 53 is an exploded left side view thereof;
FIG. 54 is a rear view of the latching portion of the lock;

FIG. 55 is a top plan view of the assembled lock view shown in FIG. 51;
FIG. 56 is a bottom plan view of the assembled lock view shown in FIG. 51;
FIG. 57 is an exploded perspective view of a ninth embodiment of my new design, the opposite side of the lock being a mirror image;
FIG. 58 is a perspective view thereof showing the latching portion engaged with the received portion, the opposite side of the lock being a mirror image;
FIG. 59 is an exploded front view thereof, the rear view being substantially a mirror image;
FIG. 60 is an exploded left side view thereof;
FIG. 61 is a rear view of the latching portion of the lock;
FIG. 62 is a top plan view of the assembled lock view shown in FIG. 58;
FIG. 63 is a bottom plan view of the assembled lock view shown in FIG. 58;
FIG. 64 is an exploded perspective view of a tenth embodiment of my new design, the opposite side of the lock being a mirror image;
FIG. 65 is a perspective view thereof showing the latching portion engaged with the received portion, the opposite side of the lock being a mirror image;
FIG. 66 is an exploded front view thereof, the rear view being substantially a mirror image;
FIG. 67 is an exploded left side view thereof;
FIG. 68 is a rear view of the latching portion of the lock;
FIG. 69 is a top plan view of the assembled lock view shown in FIG. 65;
FIG. 70 is a bottom plan view of the assembled lock view shown in FIG. 65;
FIG. 71 is an exploded perspective view of an eleventh embodiment of my new design, the opposite side of the lock being a mirror image;
FIG. 72 is a perspective view thereof showing the latching portion engaged with the received portion, the opposite side of the lock being a mirror image;
FIG. 73 is an exploded front view thereof, the rear view being substantially a mirror image;
FIG. 74 is an exploded left side view thereof;
FIG. 75 is a rear view of the latching portion of the lock;
FIG. 76 is a top plan view of the assembled lock view shown in FIG. 72;
FIG. 77 is a bottom plan view of the assembled lock view shown in FIG. 72;
FIG. 78 is an exploded perspective view of a twelfth embodiment of my new design, the opposite side of the lock being a mirror image;
FIG. 79 is a perspective view thereof showing the latching portion engaged with the received portion, the opposite side of the lock being a mirror image;
FIG. 80 is an exploded front view thereof, the rear view being substantially a mirror image;
FIG. 81 is an exploded left side view thereof;
FIG. 82 is a rear view of the latching portion of the lock;
FIG. 83 is a top plan view of the assembled lock view shown in FIG. 79; and
FIG. 84 is a bottom plan view of the assembled lock view shown in FIG. 79.

UNITED STATES PATENT AND TRADEMARK OFFICE
CERTIFICATE OF CORRECTION

PATENT NO. : Des.276,130

DATED : October 30, 1984

INVENTOR(S) : URS GISIGER

It is certified that error appears in the above-identified patent and that said Letters Patent is hereby corrected as shown below:

Page 2, at the bottom of the right-hand column, and after the description of Figure 84, please insert the following paragraph:

--It should be understood that the metallic surface finish of the lock includes two colors to provide contrast emphasis. The housing of both lock portions is formed of chrome-plated brass, and the border areas shown in stippling are devoid of chromium plating, so that the brass finish is apparent.--

Signed and Sealed this

Nineteenth Day of March 1985
